ATTORNEY.

UNITED STATES PATENT OFFICE.

HAROLD GORDON STALKER, OF NAVAN, ONTARIO, CANADA.

AUTOMATIC RECORDER FOR TELEPHONE-MESSAGES.

1,173,754.

Specification of Letters Patent. Patented Feb. 29, 1916.

Application filed February 15, 1914. Serial No. 8,408.

To all whom it may concern:

Be it known that I, HAROLD GORDON STALKER, a citizen of the Dominion of Canada, residing at Navan, in the county of 5 Russell, Province of Ontario, Canada, have invented certain new and useful Improvements in Automatic Recorders for Telephone-Messages, of which the following is a specification.

10 This invention relates to certain new improvements or attachments used in connection with telephones, and the objects and nature of the invention will be readily understood by those skilled in the art, in the light 15 of the following explanation, of the accompanying drawings illustrating one of the constructions or arrangements, embodying the fundamental principles of my invention.

10 The particular object of the invention is to 20 provide a means by which a telephone message will be automatically recorded, should there not be any person at the telephone to receive the message. The arrangement comprises a case which is attached to a recording-instrument in any desired manner suitable to the particular style of recording-instrument on which my invention is attached. 25 In the accompanying drawings I have shown my invention as attached to the body of one 30 style of a recording-instrument, but I do not wish to be limited, in any way, to using my invention in connection with this particular recording-instrument, as by slight changes it can be arranged to be connected to any 35 recording-instrument without departing from the spirit and scope of this invention.

40 The case is provided with a lever, having an arm protruding through the top of the case and having two branch arms extending and fitting over the regulating buttons of the recording-instrument. One end of the lever is hinged on the side of the case while the other end is fitted so as to be attracted by an electric magnet. Also, connected with the 45 lever is another arm branching off from the side, at right angles to the other arm, and having its outer end so arranged to fit under the arm holding a telephone-receiver of a telephone, which sits on a shelf attached to 50 the side of the case.

The invention further comprises an attachment to connect on to the poles of the telephone-receiver. The wires from this attachment run inside the case, connecting with a magnet, having an armature which causes a connection of another circuit, coming from the connection in the recording-instrument, which acts on the magnet attracting the lever mentioned above and causes the same to be attracted. When this lever is 60 attracted down the two arms on the top of the case press the buttons controlling the recording-instrument and put it in motion, and the telephone-receiver is also raised by action of the other arm and thus will allow 65 the message to pass from the telephone-receiver through the receiver of the recording-instrument and recorded on the disk or cylinder of the same. As soon as central cuts the connection off, the receiver will be restored to its normal position and the arms at the top of the case will come up, and thus take the pressure off the buttons on the recording-instrument and causes it to stop. 70

75 The invention consists in certain novel features in connection and combinations and arrangements as more fully and particularly set forth and specified hereinafter, and pointed out in the claim.

80 Referring to the accompanying drawings, like numerals designate like parts throughout and are referred to in the following specification by the same numeral.

85 Figure 1 is a perspective view of the invention as attached to a particular recording-instrument. Fig. 2 is a view of the invention, looking down on it with the top taken off. Fig. 3 is a section view of the plug or attachment connecting to the telephone-receiver. Fig. 4 is a cross-sectional view of the magnet 90 switch. Fig. 5 is a section view of the lever switch.

95 Referring to the drawings, in detail, 6 designates generally a recording-instrument, having a plate 7 in which the various keys 8, for regulating the recording instrument 9 work.

9 is a case attached to the recording-instrument 6 in any desired manner but herein shown attached by the screws 10.

10 11 is a lever attached and hinged to the

side of the case 9 at 12 and having its opposite end 13 so arranged that it will be attracted by the electric magnet 14.

15 is an arm rising perpendicular, from 5 the lever 11, for a distance sufficient to allow it to protrude a slight distance above the top of the case 9 and then it branches off in two directions to have its end fit over the buttons 8, that regulate the recording-instrument 6.

16 is another arm of the fulcrum 11, hinged at 17 and being mounted on the fulcrum 18. Arm 16 extends through the opening 19 and has its outer end 20 so shaped 15 to fit under the arm 21 of the telephone-receiver 22 of a telephone 23 which sits on the shelf 24 and kept in position by the clamps 25.

26 is a plug or attachment, having connecting members 27^a and 27^b, which connects with the two poles of the telephone-receiver 22. The connecting member 27^b is provided with a spring 28 which causes the connecting-members 27^a and 27^b to clamp 25 the poles of the telephone-receiver 22 securely.

29 is a small plug in the side of the attachment 26 used to open the connecting-members 27^a and 27^b in clamping them on 30 the poles of the telephone-receiver 22. Wires 38 connect with the inner ends of the connecting members and the armature 30 and the electric magnet 31. Said armature 30 has one end so provided with a circuit closer 35 32 so arranged as to make the connection of the wires 33 and 34. The wire 34 comes from the circuit of the recording-instrument and wire 33 connects with the electric magnet 14.

40 36 is a wire coming from the circuit of the recording-instrument 6 and connects with the end 35 of the lever 11.

37 is a spring attached to the top of the case 9 and to the lever 11, and holding the 45 said lever up.

39 is a set of wires running from the wires 38 to the shutter window 40. This shutter is of the ordinary style operated by a small magnet and operates the sign 41.

50 Now it will be seen, that when central connects any other telephone with the one using my invention, she will cause an electric current to pass through the wires of the telephone-receiver, which will go through 55 the attachment 26 along the wires 38 to the magnet 31 and cause armature 30 to be drawn to the magnet. When the armature is attracted, it will cause the connection of the wires 33 and 34. Now these wires will 60 cause action of the magnet 14 and will draw the end 13 of the lever 11 down, thus also bringing the arms 15 which will press down the keys 8 of the recording-instrument and set the instrument in motion. Also, the 65 hinged end of the arm 16 at 17 will be

pressed down thus causing the end 20 to go up, and as the end 20 is fitted under the telephone-receiver arm 21 when the end goes up, it will also cause the telephone-receiver 22 to be carried up. Now the connections 70 are all made and the message will pass through the telephone-receiver 22, through the recording-instrument's receiver 42 and be recorded on the disk of cylinder of the recording-instrument. It will also be seen 75 that the current will pass through the wires 39 connected to the wires 38, and cause the sign to drop.

Now it will be seen that as soon as central closes off the connection, the magnet 31 80 will lose its power and the armature will go back to its normal position, thus cutting off the connection of the wires 33 and 34 and causing the lever 11 to be brought back to its normal position by aid of the spring 37. 85 This will release the keys 8 and the motion of the recording-instrument will stop.

All that is necessary for a business man to do when he is going away from his office and he desires to attach the recording-device 90 to his telephone, is to set the telephone on the shelf 24, with the base under the clamps 25 and the arm 16 under the arm 21 of the telephone. Also, attach the plug attachment 26 to the poles of the receiver 22. 95 When he comes back it will at once be visible by looking at the shutter 40, if there have been any calls made while he was out and if there has been any, they will be recorded on the disk or cylinder of the recording-instrument and can be taken from there in the usual manner.

Now it is evident that various changes and modifications might be resorted to without departing from the spirit and scope of this 105 invention and hence I do not wish to limit myself to the exact disclosure hereof.

Having thus described my invention, what I claim to be new is:—

In a combination, a case, attached to a 110 recording-instrument, said case being provided with a lever hinged at one side of said case and having arms branching off from the said lever, one of the said arms branching off and protruding through the top of the said case, said arm then so shaped as to fit over the buttons that regulate the recording-instrument, the other said arm branching off from the said lever and extending through one side of the said case, 115 one end of said arm being hinged to said lever, the other end of said arm being fitted so as to fit under the arm of a telephone-receiver, said arm being mounted on a fulcrum inside of said case, a magnet in said case so situated as to attract one end of said lever, a circuit therefor, said lever having a spring connecting with the top of the case, said case being further provided with a relay and an attachment plug, said plug con- 120 125 130

necting the poles of the telephone-receiver to respective wires which connect with said relays inside said case, the armature of said relay when attracted causing the closing of 5 said electric circuit to cause the said magnet to act on said lever, said case being further provided with a shelf on which to set the telephone, and a shutter on one side con-

nected with the relay armature and operated thereby.

10

In testimony whereof I affix my signature in the presence of two witnesses.

HAROLD GORDON STALKER.
